UNITED STATES PATENT OFFICE.

CHARLES W. SAMPSON, OF DANVILLE, VIRGINIA.

ADJUSTABLE MEASURE.

SPECIFICATION forming part of Letters Patent No. 416,378, dated December 3, 1889.

Application filed March 14, 1889. Serial No. 303,342. (No model.)

To all whom it may concern:

Be it known that I, CHARLES W. SAMPSON, residing at Danville, in the county of Pittsylvania and State of Virginia, have invented certain new and useful Improvements in Measures, of which the following is a specification.

My invention relates more particularly to that class of measures known as "grocers' measures;" and it has for its object to provide a measure having a movable bottom, which can be quickly adjusted so as to measure different quantities, such as pecks, half-pecks, &c.

My invention consists in certain novel features of construction and peculiar combination of parts, as will hereinafter be fully described in the annexed specification, and particularly pointed out in the claims, reference being had to the accompanying drawings, in which—

20 Figure 1 is a top plan view of my improved measure. Fig. 2 is a cross-section of the same on the line 2 2, Fig. 1. Fig. 3 is a detail view in perspective, showing one of the vertical notched guide and supporting plates. Fig. 4 is a bottom plan view of a modification; and Fig. 5 is a cross-section of the same on the line 5 5, Fig. 4.

In carrying out my invention I provide the body A of the measure with a series of notches 30 or depressions adapted to engage with a series of projections on the movable bottom B. In arranging the said projections on the bottom I prefer to connect them therewith, as shown in Figs. 1, 2, and 3, or I may arrange them as shown in Figs. 4 and 5.

By the construction set forth in Figs. 4 and 5, I arrange the depressions a a in a series, and each series in the same horizontal plane, and provide the lower face of the bottom 40 with projecting arms b b, which are arranged to be drawn from contact with the depressions by means of a push-rod, which is spring-actuated to normally force said arms into the depressions. The spring 1 is disposed about the upper end of the push-rod 2 and connects with the upper end of the rod 2, its lower end resting on the upper side of the bottom B, thereby forcing said rod normally upward. C denotes a hollow knob fitted over the upper 45 end of the rod 2 and the spring. 44 are links pivotally connected at one end to the push-

rod and at their outer ends to the projecting arms b b, as shown. By pressing upon the knob C the rod 2 will be forced downward, thereby pulling the arms b b out of the depressions a a, and permitting the bottom to be moved up or down, as may be desired.

By the construction shown in Figs. 1, 2, and 3 a series of vertical plates D are provided, which are secured upon the inner face of the body A, and are each provided with a central vertical slot d, which communicates with a series of lateral notches a', having lower extended portions a² a³. I also provide one of the vertical edges of said plates with notches 65 a³ a³, which engage with locking-gates secured upon the bottom B, for a purpose presently described.

When the vertical plates D are employed, I provide the bottom with recesses or cut-away portions b² in the peripheral edge thereof, said recesses being of a slightly-greater width than the plates D.

E E denote crossed rods or bars fixedly secured upon the under side of the bottom B, 75 the outer ends extended, forming the projections b b, which engage the notches a' a' of the plate D.

In fitting the bottom within the body, the same is inserted therein from the bottom, the projecting arms b fitting the central slot d, the recesses b² embracing the plates D. The said bottom is then pulled upward to the desired height, (a knob C' being provided for conveniently handling the bottom,) the same 85 is then given a slight turn to the right, (see arrow, Fig. 1,) which will cause the projections b b to engage the notches a' a', and by releasing the hold on the knob the projections b b will become seated in the lower portion a² a³ of the notches, and be thereby prevented from horizontal movement.

To form an additional rest for the bottom when adjusted in place, I provide the edge d² of the plates D with elongated notches d³, 95 with which engage the edges b³ of the bottom, as clearly shown in the drawings.

It will be seen that when the bottom is adjusted in place, as just described, an opening g will be left between one side of each 100 of the vertical plates D and the edges b⁴ of the recesses b². To prevent any of the ma-

material being measured from passing through the said openings, and also to provide a convenient means for locking the bottom in place, I provide locking-gates F F, which are clearly illustrated in Fig. 3. Said gates are pivoted, as at f, to the upper face of the bottom, and are each provided with projections f' and f'', one of which f' engages the slot d, and the other f'' the notch a³ when they are swung in their locked position. Their outer ends f'' are extended and form covers for the opening g, as shown. When it is desired to change the measure, say from a half-peck to a peck, (the bottom being in its central position, as shown in the drawings,) the gates are swung back to the position shown in dotted lines, Fig. 1. The bottom is then slightly raised, so as to bring the arms b in line with the slots which connect the notches a' with the vertical slot d. The bottom is then given a slight turn to the left (see dotted arrow, Fig. 1) until the arms register with the slot d. It is then lowered to the proper depth and again adjusted to the lower set of notches in a manner previously described.

To keep the bottom from becoming detached after being once fitted within the body, I close the lower end of the slot d, as shown.

I do not confine myself to the exact construction set forth for adjusting the bottom within the body of the measure, as that may be accomplished in various ways without departing from my invention.

From the foregoing it will be seen that my invention is exceedingly simple, inexpensive, and produces a measure the advantages of which will be readily appreciated by the grocery trade.

Having thus described my invention, what I claim is—

1. The combination, with the body A, having a series of vertical plates D, provided with lateral notches, of the bottom B, provided with recessed portions embracing said plates, one edge of said recessed portions adapted to engage the notches when the bottom is turned horizontally, substantially as shown and described.
2. The combination, with the body A and the vertical plates D, provided with lateral notches d³ a³ in their edges, of the bottom B, provided with recessed portions b², adapted to embrace and fit over the plates D, said recesses b² being of a greater width than the plates D, the edges b³ of the bottom adapted to engage the notches d³ of the plate when turned in place, and locking-gates pivoted on the bottom, adapted to close the open portions of the recesses and engage the notches a³ in the plate, substantially as and for the purpose described.
3. The combination, with the body A, the vertical plates D, having each a central slot, and lateral notches a', communicating with said slots, said notches provided with a depending portion, of the bottom B, provided with lateral projections, said projections arranged to engage the vertical slots during the vertical movement of the bottom, and adapted to engage the lateral notches a' when the said bottom is turned in place, substantially as shown and described.

CHARLES W. SAMPSON.
